ABSTRACT OF THE DISCLOSURE

For use on an internal combustion engine including a cam shaft with a drive gear for driving a distributor shaft and having an access opening for the distributor shaft, the improvement comprising a mounting means for the distributor casing, the distributor shaft being in two portions which are inter-connected by a connection of common eccentricity, with one portion of the shaft being captivated in the mounting means and with the other portion being captivated in the casing, and which includes relative adjustment means to advance or retard the spark with respect to the predetermined angular position of the distributor shaft.

This invention relates to an improved distributor system which includes a mounting means with a shaft captivated therein, and, when the mounting means is connected to an engine block, the shaft is at a predetermined position of angular adjustment with respect to a cam shaft in the engine so that the timing of the engine is secured. The captivated shaft is provided with an eccentric connection with the distributor shaft which in turn is captivated in a distributor casing so that at all times when the casing and mounting means are inter-connected, the timing of the distributor is at the predetermined optimum position selected by the manufacturer. The invention also provides adjustment means for advancing or retarding the spark, and, once selected, for removal of the distributor casing and operative elements from the mounting means without intervention with the advance or retard position of the operative elements of the spark-making mechanism.

It is, accordingly, an object of this invention to provide a two-part ignition distributor housing which includes mounting means arranged to maintain the distributor shaft in an optimum position predetermined and selected by a manufacturer and which permits of relative adjustment with respect to the optimum position for the advance and retard of the spark to fit the particular desires of a user, such as to accommodate the type of gas being used, the latter being a limited range of adjustment with respect to the predetermined optimum position selected by the manufacturer.

It is another object of this invention to provide an improved distributor housing which is simple in construction, inexpensive to manufacture, and is otherwise well adapted for the purposes for which the same is intended.

In accordance with these and other objects which will become apparent hereinafter, the instant invention will now be described with reference to the accompanying drawings in which:

FIGURE 1 is an elevation view of the invention;

FIGURE 2 is an elevation view taken in cross section of the invention shown in FIGURE 1; and

2

FIGURE 3 is a view which has been partly exploded and which is in elevation for purposes of illustration of the invention shown in FIGURES 1 and 2.

Referring to the drawings, wherein like reference characters designate like or corresponding parts throughout the different views, and referring particularly to FIGURE 3, it will be seen that the housing is adapted to be mounted to an engine generally designated by the numeral 12 which includes a housing 14 having a driven shaft 16 with a gear 18 and an access opening 20 for penetration of a shaft 22 carrying a gear 24 on the end thereof to inter-engage with the gear 18. The distributor housing unit is generally designated by the numeral 30 in FIGURES 1 and 2 and includes a mounting means 32, the distributor shaft 22, a casing 34 and a cover member 36, the said cover member 36 and casing 34 defining an interior operating chamber 38 in which the conventional breaker cam contact points and condenser are positioned on a plate 40. A timing ring 42 having an upstanding key 44 to mate with a recess 46 in the exterior surface of the casing 34 is adjustably mounted for circumferential movement on the mounting means 32 for relative movement of the casing 34 and mounting means 32 with respect to a scale 52 on the casing 34 with respect to a pointer 54 on the mounting means 32. It will be noted that the shaft 22 is in two portions, a lower portion 100 and an upper portion 102; and that the two portions are interconnected by eccentric means to rotate as a unit when assembled in a fixed angular relation so that the angular relation of the upper rotor end 35 does not vary with respect to the lower portion 100.

Referring more detail to the mounting means 32, it is seen that it includes a lower stem portion 70 with an intermediate exterior enlarged portion 72 intermediate the stem length to cover the opening and which includes holes adapted for the passage of anchoring means, such as the screw 74, to interengage companionate holes 76 in the housing 14. The distal portion 80 of the stem 70 is of a length such that the terminal end 82 is adjacent the cam shaft 16 and gear 18. The upper end of the stem 70 of the mounting means 32 is provided with a cradle 84 having a recess 86 adapted to receive the casing 34. It will be seen that a through bore 90 is provided in the mounting means which is counter-bored as at 92 to provide a submerged floor 94 and the recess or cradle floor 96. The distributor shaft 22 is in two portions, a lower portion 100 and an upper portion 102. With reference to the lower portion 100 an enlarged head 103 is provided which is adapted to nest on the submerged floor 94 with the shaft lower portion depending through the bore of the stem extending through and beyond the terminal end of the stem and with said gear 24 being secured thereto by suitable means as by the fastening means 104. In the head an eccentric recess 110 is provided, and, as will be described more fully hereinafter, the upper portion 102 of the shaft 22 is provided with a male portion 112 of common eccentricity to that of the head recess 110 so that the shaft portions 100 and 102 may be interconnected.

Referring to the casing 34, it is seen that it comprises a conventional cup-shaped unit having side walls 114 circumscribed about the floor 116 of a well 118 which together with the hollow 120 of the cover member 36 define the operating chamber 38. The casing is provided with an axial bore 122 sized to rotatably receive the upper shaft

portion 102 to which operative elements of the distributor are connected. The casing 34 nests within the cradle 84 and its supported on the floor preferably by a neoprene gasket 124. It will be seen that by reason of the common eccentricity of the two portions of the shaft 22, the casing and cover member may be removed from the mounting means 32 by disengaging the clamp means 130; and that after any repair work has been done, the casing 34 may be repositioned in the mounting means without in any way changing or affecting the angular position of the shaft. The clamp means 130 comprises in the preferred embodiment a body 132 having a member 134 extending outwardly of one end and pivotally connected as at 136 to a loop 140 on the timing ring 42. A spring is provided to hold the lever in a normal position and an upper arm 146 extends from the other end of the body and includes the clamping finger 146 to inter-engage with a ledge 150 annularly circumscribed about the cover member 36.

Thus, the manufacturer may be positioning the mounting means 32 with the lower portion of the shaft 100 secured therein on the engine housing or block 14 insure that proper timing or the predetermined standard for the timing will be maintained at all times and that the distributor casing 34 together with its carried upper portion of the shaft 102 may be removed to work, for instance, in a well lighted location and, thereafter, be repositioned with the common eccentricity of the inter-connecting means 110 and 112 of the shaft portions 100 and 102 requiring that the timing will not be disturbed.

Means are also provided for advancing or retarding the spark with respect to the aforesaid predetermined standard of timing. The means comprise the timing ring 42 which is carried on the exterior of the mounting means and which may be adjusted by unscrewing the screw 162 so that it may be adjusted in the slot 166 moving the key 44 and, consequently, the angular position of the casing 34 in the cradle 84 and, consequently, the position of the contact points 186 secured on the floor 188 which is keyed for movement with the casing 34.

Thus, there is provided by the structure disclosed herein in a two-part ignition distributor housing which includes a lower mounting means with a captivated shaft portion which is arranged to inter-connect with the cam shaft and insure that an inter-connecting shaft portion will always be driven to a common eccentric inter-connection at a predetermined angular position to provide a base timing standard with respect to which the spark may be advanced or retarded by manipulation of the casing 34 and which casing 34 may be removed by a mechanic and replaced without difficulty in the predetermined position both with respect to the manufacturer's predetermined optimum timing conditions and by reason of the key 44 mating with the recess 46 in the predetermined advance or retard position. It will also be apparent with respect to the clamping means 130 that by reason of the lower foot portion 190 of the member 134 a stop is provided to limit pivotal movement of the clamp means 130, particularly the arm 146 so that it does not fall down into an inconvenient or out-of-the-way position. To facilitate lubrication of the two-piece shaft a spiral groove is provided, the groove being designated by the numeral 192 in the upper portion 102 and by a numeral 194 in the lower portion 100. A suitable feed line 196 is provided to an annular groove 198, the said feed line preferably being provided with an enlarged mouth 199. Similar type annular grooves 198' and 198'' are provided in the lower shaft portion 100, and to reduce frictional forces resisting rotation of the shaft the distal-most portion of the stem housing the lower shaft portion 100 is flared outwardly as along the line indicated by the numeral 197.

It will be apparent that the upper shaft portion 102 is rotatably captivated in the casing, as is the lower portion 100 in the mounting means, the upper portion 102 being held thus by the pin 23 and keeper ring 25 together with the head 27. As will be understood in the art, because

5 the casing 34 carries, by the screws 39, the advance retard mechanism 101, when the position of the timing ring 42 is changed, the position of the advance retard mechanism is also changed and also the angular position of the plate 40, so that in response to changes of pressure in the carburetor to operate the advance retard mechanism there will be a change with respect to the new position.

10 While the instant invention has been shown and described herein in what is conceived to be the most practical and preferred embodiment, it is recognized that departures may be made therefrom within the scope of the invention, which is therefore not to be limited to the details disclosed herein but is to be accorded the full scope of the claims so as to embrace any and all equivalent apparatus and articles.

15 I claim:

1. For use on an internal combustion engine, including a camshaft with a drive gear in the engine and an access opening to communicate with the drive gear, a two-part 20 ignition distributor housing comprising:

a first and a second part,

(i) said first part including a mounting means including a stem depending from a body with a cradle recess in said body and said body being adapted to be connected to the engine over said opening with said stem in the opening;

said means including a through-bore to connect the recess and the opening through the stem;

a first shaft portion rotatively captivated in said bore with one end of the shaft being at all times exterior of said stem and with the other end being in the cradle recess, said shaft having a gear keyed on the extending end and adapted to interengage with the drive gear; and

means to secure the first part over the engine opening; and

(ii) said second part including

a distributor casing sized to nest in said cradle recess and having a through-hole in alignment with said bore;

a second shaft portion captivated in the hole of said distributor casing with one end inside the casing and the other end extending into said bore; and

(iii) eccentric drive means to interconnect the shaft portions when the casing is nested in said mounting means and

(iv) means interconnecting the casing and the body to maintain said casing and said body in a predetermined angular position with respect to one another about the axis of said shaft portions when the casing is nested in the cradle recess; and said means interconnecting the casing and the body comprises a standard on the body and a mating recess in the casing so that, when the standard is in the recess, the body and the casing are held in a predetermined angular relation with respect to one another and the axis of the shaft.

2. The device as set forth in claim 1 wherein the standard is adjustably mounted to the body to vary said angular relation.

3. The device as set forth in claim 1 wherein a ring is provided on the exterior of said body and said ring having a circumferential slot and a headed pin secured in the slot and in clamping engagement of the ring to the body 65 whereby the position of the ring may be circumferentially adjusted with respect to the pin and clamped into position by said pin, and said standard is disposed in upstanding relation from said ring with the terminal end of the standard being adapted to interengage in the recess.

4. The device as set forth in claim 1 wherein said cradle

recess includes a central submerged floor and said eccentric drive means is nestled on the submerged floor.

5. The device as set forth in claim 1 wherein the eccentric drive means comprises an axially extending pin which is radially offset in one end of one shaft and a axially extending recess of common eccentricity in the confronting end of the other shaft portion and sized to receive the pin therein in a driving eccentric connection.
